United States Patent Office.

ROBERT WALLACE, OF WALLINGFORD, ASSIGNOR TO THE MERIDEN BRITANNIA COMPANY, OF MERIDEN, CONNECTICUT.

Design No. 4,072, dated May 24, 1870.

DESIGN FOR SUGAR-TONGS.

The Schedule referred to in these Letters Patent and making part of the same.

To all whom it may concern:

Be it known that I, ROBERT WALLACE, of Wallingford, in the county of New Haven and State of Connecticut, have invented a new Design for Sugar-Tongs; and I do hereby declare the following, when taken in connection with the accompanying drawings and the letters of reference marked thereon, to be a full, clear, and exact description of the same, and which said drawings constitute part of this specification, and represent in—

Figure 1, a side view, and in

Figure 2, the bow or spring extended.

This invention relates to a design for the spring portion of sugar-tongs and tongs for similar purposes, and consists in the peculiar form and configuration of the edge of the spring portion or connection between the two handles, as more fully hereafter described.

A is one part, and B the other part of the handle, of any desirable style or shape, and C the spring which connects the two parts.

Starting from each handle, the spring is of equal width, or nearly so, running toward the center, where the edge is wrought into an ornamental shape, as fully shown in fig. 2.

The surface may be ornamented in any desirable style.

I claim as my invention—

The design for the spring portion of sugar-tongs, as herein illustrated and described.

ROBERT WALLACE.
